[57] CLAIM

The ornamental design for a curved tube settler module section, as shown.

DESCRIPTION

FIG. 1 is a perspective view showing my new design; FIG. 2 is a top plan view thereof;

FIG. 3 is an inside elevation thereof as seen from one end; and,

FIG. 4 is an outside elevation thereof as seen from a direction opposite that of FIG. 3.

The bottom plan view is essentially identical to the top plan view. The inside elevation as seen from the opposite end is essentially a mirror image of FIG. 3 and the outside elevation seen from the opposite end is essentially a mirror image of FIG. 4.
